UNITED STATES PATENT OFFICE.

JOHN THOMAS JONES, OF TORONTO, CANADA.

CAR-COUPING.

SPECIFICATION forming part of Letters Patent No. 483,848, dated October 4, 1892.

Application filed March 14, 1892. Serial No. 424,937. (No model.)

To all whom it may concern:

Be it known that I, JOHN THOMAS JONES, painter, of the city of Toronto, county of York, Province of Ontario, Canada, have invented 5 certain new and useful Improvements in Car-Couplers; and I hereby declare the following to be a full, clear, and exact description of the same.

This invention relates to that class of car-couplers in which the coupling-pin is pivoted in the draw-head in such a manner as to permit the link to displace it when entering the draw-head, and which will instantaneously return to its normal position and prevent the withdrawal of the link the instant the link has cleared it; and the object of the invention is to so construct the link and pin that they can be operated from the side of the car, and thus obviate the necessity of going between the cars to either couple or uncouple the same; and the invention consists, essentially, of a pin rigidly mounted on a spindle loosely journaled in suitable bearings formed in the sides of the draw-head and projecting therebeyond, 25 said pin swinging rearward into the draw-head and turning the said spindle in its bearings when struck by the link during its entrance into the draw-head, a lever connected to one or both ends of said spindle for the 30 purpose of turning the said pin rearward when found necessary to do so to release the link when uncoupling the cars, and a link consisting of a U-shaped piece of metal the ends of which are bent to form eyes, 35 through which passes a spindle loosely journaled in bearings formed in the side of the draw-head and projecting therebeyond, the said spindle flattened to provide a means for turning the eyes of the link simultaneously 40 with the said spindle, the ends of said spindle being fitted to receive a lever or levers, which project to the side of the car, the whole being constructed and arranged as hereinabove after more fully set forth in the specification 45 and more particularly pointed out in the claims.

In the drawings, Figure 1 is a front elevation of a draw-head, showing the link, the spindle on which the link is mounted, two 50 slots in the lower part of the draw-head, into

which the link drops when in its vertical position, the coupling-pin, the spindle on which the coupling-pin is mounted, and the levers for operating the coupling-pin and the link. Fig. 2 is a sectional view of two draw-heads, 55 showing them coupled by means of the link and swing-pin. Fig. 3 is a plan view showing the slots in the under side of the draw-head, the link, and the levers for operating the link and swing-pin. Fig. 4 is a view of the spindle on which the link is mounted, showing the flattened surfaces. Fig. 5 is a view of the spindle on which the swing-pin is mounted.

Like numerals of reference refer to like parts throughout the specification and drawings.

The draw-head 1 is of that type of draw-heads usually employed on freight-cars and cars of a like character. In the top of the draw-head 1 is a slot 2 to the rear of the rib 4 at the front of the draw-head 1 and entering the elongated throat 3. Formed in the sides of the draw-head 1 are two circular openings, which form the bearings for the spindle 5, fitted with a square or polygonal 70 shoulder 6, on which is mounted the coupling-pin 7, provided with an opening 8, corresponding in size and shape with the shoulder 6.

The coupling-pin 7, as shown in the drawings, is somewhat after the shape of a new moon and extends upwardly through the slot 2 in the top of the draw-head 1, the upper horn 7^a resting upon the top side of the metal at the rear of the slot 2 and the lower horn 7^b resting upon the lower inner side 1^b of the 75 draw-head 1. Extending upwardly from each end of the spindle 5 is a lug 9, fitted to receive the end of a key-lever 10, securely held in place by means of a pin 11, passing through 80 said key-lever and lug.

The lever 10 extends to the side of the car and is supported in suitable brackets fastened to the car-end. The end of the lever 10 is cranked to provide sufficient purchase to readily operate the coupling-pin 7. If 85 found convenient, a lever may be attached to each end of the spindle 5, so that the coupling-pin 7 can be operated from either side of the car. Each draw-head is provided with a link 12, consisting of a U-shaped piece of 90 100

metal of any desired length and thickness, bent at its inner ends into eyes 12^a, flattened on their inner side at one or more points to engage with the flattened surfaces 13^a of the 5 spindle 13, passing through them. The spindle 13 is a cylindrical piece of metal, having, as before stated, flattened surfaces 13^a, with which engage the flattened surfaces of the eyes 12^a, and is journaled in suitable bearings formed in the sides of the draw-head 1 and projecting therebeyond.

Extending outwardly from each end of the spindle 13 is a lug 14, fitted to receive the end of the key-lever 15, similar in construction to the key-lever 10 and extending to the side of the car. The turning of the key-lever 15 raises or lowers the link 12, as the case may be—that is, when it is desired to couple two cars. The lever 15 is turned to bring the link 20 opposite the mouth of the draw-head 1 and allow it to enter therein. The continued advancement of the link 12 swings the lower end 7^b of the coupling-pin 7 to follow the curved dotted line shown in the drawings until 25 the end of the link 12 has cleared the end 7^b of the coupling-pin 7, when the coupling-pin 7 instantaneously drops back into its normal position and allows the link to draw upon it. The drag of the link 12 upon the pin 7 causes 30 the horns 7^a and 7^b to bear, respectively, upon the upper side of the draw-head 1 of the lower inner side 1^b of the said draw-head, relieving the spindle 5 of a great portion of the strain. When it is found necessary to uncouple the 35 cars, the cars are backed down upon each other until the front ends of the draw-heads meet. The lever 10 is then turned to swing the coupling-pin 7 until the lower end 7^b clears the link 12, at which time the engineer 40 can be signaled to pull forward. Immediately the link 12 has been withdrawn from the adjacent draw-head of the next car, it drops into the vertical position shown in Fig. 45 2 of the drawings, two slots 16 being formed in the under side of the draw-head for that purpose. The slots 16 are formed in the under side of the draw-head 1 and extend inwardly from the front face of said draw-head, and are so located as to receive the side 50 bars 12^b of the link 12. By providing each draw-head with a link 12 the inconvenience and annoyance of lost and broken links is entirely avoided, as there are always two links for each pair of draw-heads, and as the link 55 are securely fastened to its respective draw-head it is impossible for it to be removed without special tools for that purpose.

Having thus fully described my invention, what I claim as new, and desire to secure by 60 Letters Patent, is—

1. A car-coupler consisting of a draw-head, a slot formed in its upper side, a coupling-pin pivoted in the draw-head, one end of which rests upon the inner side of the bottom of the draw-head and the other end extending through the said slot and curved to

rest upon the metal surrounding said slot, a U-shaped link the ends of which are bent to form eyes, a spindle passing through said eyes and journaled in the sides of the draw-head, the ends of said spindle fitted to receive a lever extending across the end of the car to the sides and adapted to raise the link to enter the adjacent draw-head of the next car, and slots formed in the under side of the draw-head to receive the side bars of the coupling-link when the coupling-link is in its vertical position, substantially as described. 70

2. A car-coupler consisting of a draw-head having a slot formed in its upper side to the rear of the rib at the front of said draw-head, a curved coupling-pin mounted on a spindle journaled in suitable bearings formed in the sides of the draw-head, one or both ends of said spindle fitted to receive a lever extending across the end of the car to the sides, said pin adapted to be turned rearward and upward by said lever, a U-shaped link the ends of which are bent into eyes the inner sides of which have one or more flattened surfaces, 85 a spindle passing through said eyes having flattened surfaces to engage with the flattened surfaces of the eyes, one or both ends of said spindle fitted to receive a lever extending across the end of the car to the side 90 and adapted to raise the coupling-link to enter the adjacent draw-head of the next car, and two longitudinal slots formed in the under side of said draw-head, which receive the side bars of the coupling-link when in its vertical 100 position, substantially as described.

3. A car-coupler consisting of a draw-head having a slot formed in its upper side and to the rear of the rib at its front end, two slots formed in its under side, extending longitudinally inward from the front of said rib, a U-shaped coupling-link the ends of which are bent into eyes having their inner surfaces flattened, a spindle passing through the said eyes and journaled in suitable bearings 105 formed in the sides of the draw-head, said spindle having flattened surfaces to engage with the flattened surfaces of the said eyes, a lug extending outwardly from one or both ends of said spindle, fitted to receive the key-lever rigidly connected to said lug by means of a pin passing through said key-lever and lug, said key-lever extending across the end of the car to the side and cranked at its free end, said coupling-link adapted to be raised 110 into a horizontal position by the movement of said lever and the side bars of the link entering the slots in the under side of the draw-head when hanging in its vertical or normal position, a coupling-pin located within the 115 draw-head and having a polygonal opening therethrough through which passes a correspondingly-shaped spindle, the ends of said spindle journaled in bearings formed in the sides of the draw-head, and a lug projecting 120 outwardly from one or both ends of said spindle and fitted to receive a key-lever rigidly con- 125

nected to the said lugs by means of pins passing through the said key-lever and through the said lug, said lever extending across the end of the car to the side and having its free end cranked, said lever adapted to turn the coupling-pin rearward and upward when uncoupling the cars, said coupling-pin extending upwardly through the slot in the upper

side of the draw-head and curved to rest on the surrounding metal, substantially as described.

Toronto, February 18, 1892.

JOHN THOMAS JONES.
